UNITED STATES PATENT OFFICE

2,443,193

VALVE SPRING COMPRESSOR

George J. Necker, United States Navy

Application April 20, 1945, Serial No. 589,437

1 Claim. (Cl. 29—219)

(Granted under the act of March 3, 1883, as
amended April 30, 1928; 370 O. G. 757)

1

This invention relates to means for assisting in the removal or insertion of valve springs in internal combustion engines, and more specifically to a tool for compressing a valve spring.

Most valve springs are stiff and it is difficult to hold the spring in compression for removal or insertion because of the lack of convenient means for exerting sufficient pressure on the spring to compress it and to hold it compressed while the spring retaining means is removed from or is inserted into the valve stem. Furthermore, difficulty is frequently encountered in overhauling motors because the valves are so close together that it is impossible to use the ordinary valve spring compressor without interference from an adjacent valve spring.

Hence, it is an object of the present invention to provide an improved valve spring compressor which is adapted to simultaneously compress and hold one or more valve springs compressed while the retaining means is being removed from or inserted in the valve stem, which is simple in construction and which is readily operable.

With the aforesaid objects in view, invention resides in a valve spring compressor comprising means adapted to be anchored to the cylinder head, means associated with the first named means adapted to bear against an end of a valve spring to be compressed, means mounted on the first named means operable to move the second named means in a direction to cause the second named means to compress the spring, and means for effecting operation of the last named means. As illustrated, the device is especially adapted for compressing a plurality of valve springs simultaneously, and consists of a post adapted to be anchored to the cylinder head centrally of a plurality of valves, by a latch pivoted to the lower end of the post for engagement with the underside of the head. Arranged to slide on the post, is a sleeve to which are pivotally secured a pair of cams. A plate is also slidably mounted on the post for movement in a plane perpendicular to the post, the plate being adapted to engage the tops of the springs to be compressed and the sleeve being slidably along the post to bring the cams into engagement with the plate. Means is provided for securing the sleeve to the post when the cams engage the plate and means is also provided for actuating the cams to depress the plate, thereby to compress the springs.

The invention will now be described with reference to the accompanying drawings, in which:

Fig. 1 is an elevational view of my improved valve spring compressor; and

2

Fig. 2 is an end elevational view of a block which forms a part of my improved valve spring compressor.

Referring to Fig. 1, my improved valve spring compressor is illustrated generally by the reference character 10 in an operative position, that is, partially compressing a plurality of internal combustion engine valve springs 12 which surround valve stems 14 of a plurality of valves 16 which are shown diagrammatically associated with a cylinder head 18. While the valves illustrated are quadruple overhead valves such as are commonly employed in internal combustion engines of the General Motors type, it is to be understood that 15 the device can be used with equal effectiveness for other valves.

The device comprises a post 20 adapted to be inserted through an opening 21 in the cylinder head in a substantially vertical position and is 20 locked against withdrawal from the opening by a latch 22 pivoted at 24 on the lower end of the rod, the latch being adapted to engage the under side of the cylinder head. Mounted for movement along the post is a block 26 which is shown 25 in Fig. 2, to have a central aperture 19 adapted telescopically to fit the post and a pair of slots 23 therein adapted to receive a pair of cams 30. The cams 30 are pivotally mounted in the slots 23 on a pair of bolts 32, the latter being threaded 30 through apertures 33 in the opposite walls of the slots 23. There is also mounted on the post 20 a plate 34 which is adapted to move along the post in a plane which is perpendicular thereto and has apertures 36 and 38 formed therein. The 35 aperture 36 is of sufficient size to fit over the post 20 and to permit free movement of the plate along the post and the apertures 38 are of sufficient size to fit over the ends of valve stems 14. The number, size and disposition of the apertures 38 40 in the plate 34 will be determined by the number of valves, the size of the valve stems and the disposition of the valves. The plate 34 when mounted on the post 20 is adapted to be moved into engagement with the retaining washers 40 45 against which the valve springs 12 bear, the plate being designed to engage the ends of a plurality of valve springs so that they may simultaneously be compressed. After the plate is brought into engagement with the ends of the valve springs, 50 the block 26 is moved along the rod 20 to bring the cams 30 into engagement with the plate and is then locked to the post by a pin 42 arranged to be inserted in an opening 43 formed diametrically through the post 20 to engage the 55 upper surface of the block 26. To prevent loss

of the pin and the block 26, it is desirable to fasten the pin to the block by means of a chain 44 attached to an eye 43 at one end of the pin and to a staple 46 fixed to the block 26. To accommodate the device for valve stems of different lengths a series of openings 48 may be formed in the post so that the block may be locked in substantially any position along the post. Only two openings 48 are shown for the purpose of illustration. A pair of arms 50 are attached to the cams 38 for rotating the same about the pivot 32 and as will be seen the cams are so shaped that movement of the arms 50 away from each other causes depression of the plate 34, and hence, compression of the springs 12 which is the condition shown in Fig. 1. It is apparent that by compressing the springs 12, the retaining means which is shown by way of illustration only as pins 52 at the ends of the valve stems may easily be removed and that if the arms 50 are then moved toward each other, the springs may be allowed to reexpand to a point where there is no longer compression in them, and hence the valve springs and valves may be released and removed.

The device as described above is designed especially for removing the valve springs from quadrupally arranged valves of internal combustion engines wherein the valves are mounted in the cylinder head and may be removed from the top of the engine. Overhead valves of this type are so close together that it is difficult to use the usual single valve spring compressor without fouling it up with the spring of an adjacent valve. In using the above described compressor for a plurality of valves, the post 20 is inserted through the opening 21 in the cylinder head 18 far enough to allow the latch 22 to pass through the opening 21 and engage the underside of the head, the plate 34 is mounted on the post 20 and moved downwardly into engagement with the upper ends of the springs 12, and block 26 is placed on the post and moved into engagement with the plate 34 and the pin 42 is inserted in the opening 48 to lock the block in place, and thereafter, the operator, by moving the arms 50 away from each other, effects downward move-

ment of the plate 34 to compress the springs 12 so that the pins 52 may be removed from the valve stems or reinserted on the valve stems depending upon whether the springs are being assembled or disassembled.

The invention described herein may be manufactured and used by or for the Government of the United States of America for governmental purposes without the payment of any royalties thereon or therefor.

What is claimed is:

A tool for compressing valve springs comprising a post having a latch near one end, a plate slidable on the post in a plane perpendicular thereto, said plate having a plurality of apertures formed therein of such diameter as to loosely fit over the end of a valve stem, a block slidable on the post, a pair of slots in the block, a pair of cams seated in said slots, bolts threaded into the block through the slots upon which the cams are pivoted, said block being movable to a position on said post to bring the cams into engagement with the plate, means for locking the block to the post and means for effecting rotation of the cams to move the plate along said post away from the block.
